(57) **CLAIM**

The ornamental design for a paper roll product holder, as shown and described.

DESCRIPTION

FIG. 1 is a perspective view of a paper roll product holder, showing our new design;

FIG. 2 is a front elevational view thereof;

FIG. 3 is a side elevational view thereof;

FIG. 4 is a top plan view thereof;

FIG. 5 is a perspective view of a second embodiment of a paper roll product holder, wherein the broken lines form no part of the claimed design and the portions of the peripheral member that are shown broken away indicate that the lengths of each of the broken peripheral member portions do not form a part of the design; and,

FIG. 6 is a perspective view of a third embodiment of a paper roll product holder, wherein the broken lines in the central vertical elements indicate the specific height of the elements and the paper product roll holder do not form a part of the design, and the portions of the peripheral base member that are broken away indicate that the length of each of the broken peripheral base member portions does not form a part of the design.

The dotted line disclosure of elements in the views is for illustrative purposes only and forms no part of the claimed design.
